UNITED STATES PATENT OFFICE.

JOSEPH I. GUNGLE, OF ANN ARBOR, MICHIGAN.

INDICATOR.

1,220,981.

Specification of Letters Patent.

Patented Mar. 27, 1917.

Application filed December 17, 1915. Serial No. 67,438.

To all whom it may concern:

Be it known that I, JOSEPH I. GUNGLE, a citizen of the United States, residing at Ann Arbor, in the county of Washtenaw and State of Michigan, have invented certain new and useful Improvements in Indicators; and I do hereby declare the following to be a full, clear, and exact description of the invention, such as will enable others skilled in the art to which it appertains to make and use the same.

This invention relates to new and useful improvements in indicators and the principal object of the invention is to provide a device which will indicate to the driver of a motor vehicle the direction in which a passenger is desirous of traveling.

Another object of the invention is to provide a means for directing the driver in event that he is not familiar with the location of various buildings and the like.

A still further object of the invention is to provide a means for indicating where and when to stop.

25 A further and more specific object of the invention is to provide a device actuating by electro-magnets which are energized upon the pressure of the passenger's thumb on certain buttons or combination of buttons.

30 With these and other objects in view, the invention consists in the novel combination and arrangement of parts which will be fully set forth in the following specification and accompanying drawings, in which:

35 Figure 1 is a view illustrating this improved device attached to a motor vehicle of the usual construction.

Fig. 2 is a vertical sectional view of the attachment.

40 Fig. 3 is a side view partly in section of the switch.

Fig. 4 is a top plan view showing the indicating hand.

Fig. 5 is a plan view showing the dial and hand removed and illustrating the interior construction of the casing.

Fig. 6 illustrates the wiring diagram.

Referring now to the drawings by characters of reference, the numeral 1 designates as 50 an entirety the supporting structure for the indicator casing comprising the base block 2 having formed at its outer end the inclined face 3. This face 3 forms the rest on which the indicator is secured.

55 The indicator casing is designated gen-

erally by the numeral 6 and comprises a cylindrical casing 7, the lower end of which is closed as at 8 and secured to the base block 2 as at 9. Formed in the outer end of the casing 7 are the threads 10, which coöperate with the threaded ring 11 in supporting the glass crystal or cover 12 which rests on the annular shoulder 13 formed on the interior of the casing.

Secured centrally of the bottom wall 8 65 of the casing is a suitable sleeve or bearing 15 in which the shaft 16 is journaled. The upper end of the shaft extends through an opening 17 formed in the dial 18 which is supported on suitable lugs 19 formed at 70 spaced intervals along the interior of the casing 7. Secured on the upper end of the shaft is a suitable hand 20 and secured near the lower end of the shaft is a sleeve 21, formed with the armature 22, which is 75 attracted by the cores of the magnet 23 as illustrated in Fig. 5. These magnets 23 are positioned at spaced intervals around the interior of the casing 7 so that their cores are disposed in such a position as to 80 attract the armature 22. Secured to the shaft 16, in angular relation to the armature and hand, is a non-magnetic weight 24 which, when none of the magnets are energized, holds the hand in a neutral or 85 non-indicating position.

A suitable sight opening 25 is formed in the dial intermediate two of the magnets 23 and a lamp bulb 26 is supported immediately beneath the sight opening 25 in a 90 suitable space.

In order to control the energization of the electromagnets 23, there is provided a suitable controller designated generally by the numeral 27 comprising a cylindrical 95 casing 28 provided with end closures 29. One of the end closures is formed with an opening 30, through which the wires enter the casing and a suitable insulating block 31 is supported on the floor of the casing 100 and forms a support for the contact members which will be more fully hereinafter described. Formed at spaced intervals at a point diametrically opposite the insulating material 31 are the openings 32 through 105 which the push buttons 33 extend. The inner ends of these push buttons bear against the contact springs 34 which are secured in any suitable manner to the insulating material. A suitable contact point 110

35 is disposed beneath the contact spring so that when its respective push button is pressed the spring 34 will be forced into engagement with the point 35 so that the 5 circuit will be completed through its respective magnet. When not in use the device is hung upon the back of the front seat of the car by the hook, as shown in Fig. 1.

Upon referring to the wiring diagram 10 illustrated in Fig. 6, it will be seen that the current passes from the battery 36 into the wire 37 and thence through the branch wires 38 into one of the contact springs 34, thence through the contacts 35 into the 15 wire 39 and to the lamp 26 hereinbefore referred to. The current then passes through a branch wire 40 into the common return wire 41 and back to the battery.

It will thus be seen that when the push 20 button designated by the character D is operated, the filament of the lamp 26 will glow and thereby illuminate the sight opening 25 to indicate to the driver to stop. Upon manipulation of the press button designated by the character A, it will be seen 25 that the current will flow through the wire 37 into the branch wire 41 through the contact of the push button A into the wire 42, thence to the magnet designated *a* and 30 through the branch wire 43 connected thereto into the common return wire 41 hereinbefore referred to. Likewise the pressure on the push button B will energize the magnet *b*, while pressure on the 35 push button C will energize the magnet *c*. The energization of these magnets will cause the armature 22 to be drawn toward the cores and the hand will move over the face of the dial to indicate the direction 40 to be taken. When none of the magnets are energized it will be seen that the weight

24 will hold the hand in a neutral position, thereby avoiding the giving of a signal.

While in the foregoing there has been shown and described the preferred embodiment of this invention, it is to be understood that such changes may be made in the combination and arrangement of parts as will fall within the spirit and scope of the appended claim. 45 50

What is claimed is:

An indicator comprising a casing electromagnets mounted within said casing and arranged in annular series, a lamp bulb within the casing in place of one magnet, 55 a sleeve secured to the bottom wall of said casing, a shaft rotatable in said sleeve, a dial secured within the casing in spaced relation to the bottom wall, said dial having a central aperture arranged therein for the reception of the shaft, said dial also having a lateral aperture formed therein to provide a sight opening through which the lamp bulb is visible, a hand secured to the outer end of the shaft and operable 60 over the face of the dial, an armature mounted on the shaft and adapted to be attracted by the electro-magnets, said magnets being adapted to be individually excited, the armature and hand extending in the same plane from the axis of the shaft, a weight mounted on the shaft and adapted to hold the hand in a non-indicating position when the magnets are deenergized and a transparent cover for the casing adapted to completely house the hand and dial. 65 70 75

In testimony whereof I affix my signature in presence of two witnesses.

JOSEPH I. GUNGLER.
